UNITED STATES PATENT OFFICE.

HENRY E. SPADONE, OF NEW YORK, N. Y.

DESIGN FOR A RUBBER MAT.

SPECIFICATION forming part of Design No. 21,730, dated July 19, 1892.

Application filed June 24, 1892. Serial No. 437,913. Term of patent 7 years.

To all whom it may concern:

Be it known that I, HENRY E. SPADONE, a citizen of the United States, residing at New York, in the county and State of New York, have invented and produced a new and original Design for Rubber Mats, of which the following is a specification, reference being had to the accompanying drawings, showing the same.

10 Figure 1 is a plan view of a mat, showing my design. Fig. 2 is a vertical cross-section of the same.

15 The leading features of my design consist of a raised oval border composed of a series of circular or approximately circular figures bounded inside and outside by an oval projection and a raised center of diamond-shaped figures.

20 α is the border, which is oblong in general contour and which is made up of the series of

circular projections a' , bounded upon each side by the oval projections b and b' . The oval projections b and b' are, as shown in Fig. 2, raised slightly higher than the circular projections a' . The center is composed of the series of projections $c c$, crossing the series of projections $d d$, so as to make diamond figures. Each projection c and d is wider at the base than at the summit; but, as shown in Fig. 2, the summits or all the projections $c d$ are below the summit level of the border projections $b b'$.

25 What I claim is—

15 The design for a rubber mat herein shown and described.

30 HENRY E. SPADONE.
